CLAIM

The ornamental design for a storage device blister tray, substantially as shown and described.

DESCRIPTION

FIG. 1 is a front perspective view of a storage device blister tray of my new design;

FIG. 2 is a top plan view thereof; a bottom plan view thereof is an identical image;

FIG. 3 is a front elevation view thereof; a rear elevation view thereof is an identical image;

FIG. 4 is a left side elevation view thereof; and,

FIG. 5 is a right side elevation view thereof.

The broken lines are for illustrative purposes only and form no part of the claimed design.
